UNITED STATES PATENT OFFICE.

PERRY E. KENT, OF NEW YORK, N. Y., ASSIGNOR TO EDWARD W. LIBBY, OF ST. PAUL, MINNESOTA.

LINOTYPE-MATRIX RESHAPER.

Application filed December 5, 1921. Serial No. 520,108.

To all whom it may concern:

Be it known that I, PERRY E. KENT, a citizen of the United States, a resident of New York city, county of Bronx, and State 5 of New York, have invented a certain new and useful Improvement in the way of a Linotype-Matrix Reshaper, of which the following is a specification.

My invention relates to improvements in 10 reshapers for rectifying distorted combinations in linotype matrices, and is particularly an improvement in the device covered by patent issued to me on June 1, 1909, Number 923,275. The improvement herein 15 consists particularly in improved means for locking the die cap or elevator in a fixed or raised position, while the matrix is being detached or pressed downward out of contact 20 with the reforming segments, and unlocking the die cap or elevator when another matrix is in position ready for another operation.

Use of the construction shown in my former patent demonstrated that in that construction the die cap was forced downward 25 by adhering to the matrix and necessitated various expedients to bring about removal of the matrix.

In order to make the device fully practical it became necessary to invent means 30 whereby the die cap or elevator could be positively locked or unlocked at the proper time and securely held in place while the matrix was being detached, and these results are accomplished in my present invention.

Referring to the accompanying drawings, 35 forming part of this specification:

Figure 1, is a perspective view of my reshaper.

Figure 2, is a vertical longitudinal cross 40 section of the same, showing the elevator locked in raised position.

Figure 3, is a similar view to Figure 2, showing the elevator in unlocked lowered position.

Figure 4, is a sectional view on line 4-4 45 of Figure 2.

Figure 5, is a perspective view of the elevator; and

Figure 6, is an elevation, partly broken 50 away, with the locking device forming part of my invention.

Referring to the drawings, "A" represents a block or base portion of my device, and "B" represents an elevator or reshaper slid- 55 ably supported upon the rear of the block

"A" through the medium of the flanges 2, extending into corresponding runways in the block "A." The block "A" is covered by the top case-hardened plates 3, secured in position by the screws 4, said plates forming a bed during the operation of the device, as hereinafter pointed out, and in operation limiting the upward movement of the slide- 60 able member "B." The member "B," as shown in Figure 5, is formed with an inwardly projecting part 5, which part 5 carries the flanges 2 and stands under the plates 3. The downward movement of the reshaper member "B" is limited by the base 65 of the block "A," the base of said block having a rearwardly extending portion 6, positioned under the member "B."

Held within an opening in the upper end and in front of the member "B," is the reshaper head 7, formed with reshaping teeth 75 8, the bed plates 3 being formed with a toothed opening 9, to receive the teeth of the reshaper head in the sliding operation of the supporting member "B." The member "B" is forced into raised position, shown in 80 Figures 1 and 2, by a coil spring 10, interposed between the bottom of the member and the projecting portion 6 of the base block.

In order to positively lock the member 85 "B" in raised position while the matrix is being detached from the reshaper, I provide a locking device comprising a slideable pin 11, positioned in an opening 12 in the inner face of the member "B," the pin being nor- 90 mally pressed outwardly by a coil spring 13 to project beyond the inner face of the member "B," as shown in Figure 5.

The coil spring 13 is preferably inset 95 within the inner end of the pin 11, as shown in Figure 6, and the pin is held within the opening 12 by a small shoulder 14, over which the inner wall of the member "B" is burried to hold the pin in position.

When the slideable member "B" is in the 100 raised position shown in Figure 2, the locking pin 11 is forced by the spring 13 into the registering opening 15, extending through the block "A," to lock the slideable member "B" in raised position. The pin 11 is forced 105 out of the opening 15 to permit the lowering of the member "B" by the following described mechanism: Slidably supported upon the front of the base block "A" is a finger grip 16, guide pins 17 being carried by the 110

finger grip and slidably projecting into the openings 18 in the base block. Anchored in the finger grip, as by being screwed therein, is an ejector pin 19, slidably projecting into the opening 15 through the base block. The coil spring 20 is positioned between the finger grip and an inwardly projecting rib 21 within the opening 15, to normally hold the finger grip pressed outwardly from the base block, as shown in Figure 2. The ejector pin, as shown, is formed with an enlarged inner end 22 upon the side of the rib 21 opposite the spring.

In use, the matrix to be reshaped is positioned upon the bed plates 9, with the toothed portion of the matrix positioned between the upper teeth and the central row of teeth of the reshaper. By then pressing inwardly the finger grip, the locking pin 11 is forced out of locking position, as hereinbefore pointed out, allowing the member "B" to be pressed down to reshape the matrix through the medium of the upper row of teeth of the reshaper. The downward pressure upon the slidable member "B" then being released, will permit the same to be forced into raised position by the spring 10. As the member "B" passes into raised position, with the pressure upon the finger grip released, the spring 13 will force the locking pin 11 into the locking position shown in Figure 2. The slidable member "B" may thus be held locked in raised position to permit the removal of the matrix. By having an upper and lower, and an inner spaced middle set of teeth upon the reshaper head, the reshaper head may, when desired, be removed by the removal of the bed plates and reversed in position.

40 I claim:

1. A linotype matrix reshaper, comprising a base portion, a reshaper member slidably supported upon said base portion, means normally holding said reshaper member locked in raised position, and a manually actuatable member operated to release said reshaper member and allowed to be depressed, for the purpose set forth.

2. A linotype matrix reshaper, comprising a base portion, a reshaper member slidably

supported thereby, spring means normally holding said reshaper member in raised position, means holding said member positively locked in raised position, and manually actuated means operative to release said locking means, for the purpose set forth.

3. A linotype matrix reshaper, comprising a base portion, a reshaper member slidably supported thereby, spring means for forcing said member into raised position, means operatively locking said member in raised position, and manually actuated means slidably supported upon said base and operative to release said locking means.

4. A device of the class described, comprising a base portion, a reshaper member slidably supported thereby, spring means for carrying said member into raised position, a spring pressed locking pin supported in said reshaper member and projecting into an opening in said base when said reshaper member is in raised position, and manually actuated means for forcing said pin out of said opening to permit said reshaper member being lowered.

5. A device of the class described, comprising a base portion, a reshaper member slidably supported thereby, spring means for carrying said member into raised position, a spring pressed locking pin supported in said reshaper member and projecting into an opening in said base when said reshaper member is in raised position, and a finger grip slidably supported upon said base and operative to engage with said pin and force it out of said opening to permit said reshaper member being lowered.

6. A matrix reshaper of the class described, comprising a base portion, a reshaper member slidably supported by said base portion, spring means for carrying said reshaper member into raised position, a reversible tooth portion removably supported by said reshaper member, bed plates supported upon said base and formed with a jaw receiving said toothed portion, locking means for holding said reshaper member in raised position, and means for releasing said locking means.

PERRY E. KENT.
